UNITED STATES PATENT OFFICE.

KARL G. FRIETSCHE, OF SCHENECTADY, ASSIGNOR TO THE EDISON MACHINE WORKS, OF NEW YORK, N. Y.

COMMUTATOR-BRUSH.

SPECIFICATION forming part of Letters Patent No. 448,331, dated March 17, 1891.

Application filed June 28, 1890. Serial No. 357,073. (No model.)

To all whom it may concern:

Be it known that I, KARL GUSTAF FRIETSCHE, a citizen of the Grand Duchy of Finland, residing at Schenectady, in the county of Schenectady and State of New York, have invented a certain new and useful Improvement in Commutator-Brushes, of which the following is a specification.

The invention relates to devices for collecting the current generated in a dynamo or magneto-electric machine and delivering the same to the translating-circuit, or for delivering the current from a supply-circuit to the armature-coil of an electric motor; and the invention consists in an improved brush having a carbon or other suitable contact-piece, which is automatically fed forward as it wears away by an adjustable spring-pressure, the current passing from the carbon contact near the commutator surface to a second brush of copper or other high conducting material; and the invention further consists in features of construction and combinations, as hereinafter described and claimed.

In the accompanying drawings, which illustrate the invention, Figure 1 is a side view, partly in section, of a commutator-brush. Fig. 2 is a detail of the copper-brush holder. Fig. 3 is a rear end view of the brush, partly in section. Fig. 4 is a side view of the copper brush, and Fig. 5 is a top view of the same.

The circle 1 indicates a commutator-cylinder of any well-known or suitable construction.

2 is an adjustable rod or pintle, movable in the arc of a circle around the commutator-cylinder and carrying one commutator-brush, whereby the position of the brush on the commutator-cylinder can be changed to regulate the generator or motor. It will be understood that a corresponding pintle on the opposite side of the commutator-cylinder carries a second brush of the same construction in the ordinary manner.

3 is a carbon block, hereinafter termed the "contact-brush," one end of which bears against the commutator-cylinder. This contact-brush is supported in the holder 4, which in turn is supported by the pintle 2.

5 is a second brush or conductor, herein-after termed the "line-brush," one end of which bears upon the carbon block near its contact end. The other end of the line-brush is supported in the socket 6, and is clamped in place by a suitable bolt 7, which preferably passes through a slot 8 in the end of the brush. The brush 5 is preferably constructed of sheet-copper and layers of copper wire alternating, the outer layers being sheet-copper. The line-wire may be clamped between the brush and the bolt-head. The holder is cut away at 9, as indicated in the drawings.

10 is a frame or device, the inner end of which rests against the contact-brush.

11 is a cross-rod, to one or both ends of which is connected a spring 12, the other end of which is coiled around that part of the holder which is journaled on the pintle 2, the holder being suitably formed to receive the spring, as shown in the drawings. The springs terminate at 13, and above or outside of the spring is a cross-piece 14, adjustable by means of a bolt 15 and thumb-screw 16, whereby the tension of the spring on the contact-brush may be varied.

It will be seen that by grasping the rear end of the frame 10 it can be retracted and held in the position indicated by dotted lines for the removal of the contact-brush or for any other purpose desired. The springs rest in notches 17, which notches prevent the forward movement of the frame beyond a certain limit, as will be evident.

To remove the contact-brush from the commutator-surface, the screw 18 is retracted and the holder turned on its pintle until the end of the screw comes in line with the bearing-surface 19, when the screw is again turned forward. This throws the lower end of the holder and the contact-brush away from the commutator-cylinder.

20 are thin sheets of copper, and 21 are layers of copper wires, preferably longer than the copper sheets. The copper plates and wires are preferably soldered together between the points 22 22', and a band is placed around the brush at 23, which serves to hold the wires from displacement, at which point

the upper plate or sheet terminates. It is not, however, essential that the line-brush should be of this exact construction.

Having thus described my invention, what

5 I claim is—

1. The combination, in a commutator-brush, of a contact-brush pressed against the commutator-cylinder and a brush to which the line is connected bearing against said contact-brush adjacent to its contact end, substantially as described.

2. The combination, in a commutator-brush, of a carbon block supported in a suitable holder, one end of the block bearing against 15 the commutator-cylinder, a spring for pressing the block forward, and a line-brush of high conductivity bearing against the block near its contact end, substantially as described.

20 3. The combination, in a commutator-brush, of a pintle or support, a holder carried thereby, a contact-brush in the holder and adapted to bear longitudinally against the commutator-cylinder, and a second brush making contact 25 with one side of the first brush and connected directly to line, substantially as described.

4. The combination, in a commutator-brush, of the pintle 2, the holder and the line-brush adjustably held thereon, the carbon contact- 30 brush in the holder, the frame bearing against

said brush, and springs the tension of which holds the frame against the brush, substantially as described.

5. The combination, in a commutator-brush, of the pintle, the holder supported thereon, 35 the line-brush, the carbon contact-brush in the holder, the frame bearing against said brush, springs the tension of which holds the frame against the brush, and means for adjusting the tension of the springs, substantially as described.

6. The combination, in a commutator-brush, of the holder 4, the contact-brush therein, the line-brush bearing on the contact-brush, the device bearing against the contact-brush and 40 the springs for pressing the same forward, and means for retracting said device and holding the same, substantially as described.

7. The combination of the holder supported 45 on the pintle, the spring-pressed contact-brush, the line-brush, and means for retracting and holding the contact-brush from the commutator-cylinder, substantially as described.

This specification signed and witnessed this 55
19th day of June, 1890.

KARL G. FRIETSCH.
